UNITED STATES PATENT OFFICE.

CHARLES D. THOMPSON, OF CHICAGO, ILLINOIS.

CRIMPING-PIN.

SPECIFICATION forming part of Letters Patent No. 234,629, dated November 16, 1880.
Application filed May 8, 1880. (No model.)

To all whom it may concern:

Be it known that I, CHARLES D. THOMPSON, of Chicago, in the county of Cook and State of Illinois, have invented certain new and useful Improvements in Crimping-Pins; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved crimping-pin with the pin in its shield, and Fig. 2 is a similar view with the pin withdrawn from its shield.

This invention has relation to improvements in crimping-pins for ladies' hair, having for its object more especially to prevent their points 20 piercing and projecting through the paper inclosing them during shipment or storage, which would, in addition to rendering the package or wrapper unsightly, endanger the bending or blunting of the pins, or make them liable to 25 prick the hands while handling them preparatory to shipment or while unshipping them; and it consists in the combination, with the pin, of a tapering shield, to which one end of its spring is attached, substantially as herein- 30 after more fully set forth.

A crimping-pin, A, as seen in the drawings, bent in the usual way with two prongs, *a a*, with divergent free ends, may be used by way of illustrating my improvement.

B is the shield or protector for the points of the pin, which tapers or converges at its sides toward its inner end, as shown, with said sides turned upwardly and over about parallel with the bottom of the shield, thus forming 40 side grooves, *b b*, for the ends or points of the pin to fit into and thus incase them, while the lower edge of the shield is in like manner turned up or doubled between the side grooves, *b b*, to form a transverse bottom groove, *c*, to 45 prevent their projecting beyond the shield or

protector and piercing the inclosing paper or material in which they may be wrapped for shipment or storage, or picking the hands while handling them previous to and after shipment or storage or while being handled 50 by the seller or customer. The convergence of the inner end of the shield or protector compresses the divergent pointed prongs of the pin, and thus causes them to bear with considerable energy against the sides of the 55 shield and effectually holds them in the shield, so as to avoid their passing this point and projecting beyond the shield or protector.

The shield may be closed or not at its outer flaring end, while the points of the pin may 60 be curved or otherwise blunted; or they may possess the usual points, which is preferable as serving greater convenience in passing the pin through the hair. The shield may be highly ornamented, if desired, to beautify its 65 appearance.

While being free from the aforesaid disadvantages, this device is also adapted to be transmitted through the mail (which is one of its principal objects) without tearing or mutilating the accompanying matter, as occurs with the mailing of other crimping-pins. As is usual, a spring, C, connects the pin to the shield.

Having thus fully described my invention, 75 I claim and desire to secure by Letters Patent of the United States—

The shield or point-protector B, having converging side grooves, *b b*, and bottom groove, *c*, in combination with the pin A, having diverging points *a a*, and spring C, substantially as set forth.

In testimony that I claim the foregoing as my own I have hereto affixed my signature in presence of two witnesses.

85

CHARLES D. THOMPSON.
